SPECTACLE AND EYEGLASS CASE

Arthur J. Pratt, Belmont, Mass., assignor to
American Optical Company, Southbridge, Mass.,
a voluntary association of Massachusetts

Application May 1, 1933, Serial No. 668,741

7 Claims. (Cl. 206—6)

This invention relates to improvements in receptacles and has particular reference to an improved case for spectacles and eyeglasses and method of making the same.

5 One of the principal objects of the invention is to provide improved means and method of making a spectacle or eyeglass case having a cover member formed with a reenforcing edge portion adapted to provide protective means 10 for preventing the peripheral edges of the case covering material on said cover member from becoming loosened or frayed during use.

Another important object of the invention is to provide a spectacle or eyeglass case with a 15 cover member having its central portion depressed, leaving a raised marginal reenforcing edge along the sides and front of the cover and a depressed marginal edge along the back or hinge side thereof adapted to form a shouldered depression in which the flexible covering material of the case may be fitted by extending the said material from the main box portion of the case through the depressed marginal edge and into the depression, with the peripheral edges of said 20 covering material abutting the shouldered portion of the depression so that it will be protected from becoming loosened or frayed during use.

Another object of the invention is to provide an improved process of making a covered case of the above character wherein portions of the metallic body of the case may be left exposed for decorative or other purposes.

Other objects and advantages of the invention will become apparent from the following description 35 taken in connection with the accompanying drawing, and it will be apparent that many changes in the steps of the process and in the arrangement of parts and details of construction may be made without departing from the spirit 40 of the invention as expressed in the accompanying claims. I, therefore, do not wish to be limited to the exact steps of the process and details of construction shown and described as the preferred form only has been shown by way of illustration.

45 Referring to the drawing:

Fig. I is a plan view of a case embodying the invention;

Fig. II is a perspective view showing a section 50 taken on line II—II of Fig. I; and

Fig. III is a fragmentary perspective view of one end of the case showing the cover portion raised.

It has been usual, in the past, in spectacle and 55 eyeglass cases of the above nature to cover the

entire case with a flexible material such as leather, imitation leather, fabric or other suitable means to provide a decorative finish. Recent changes in the design of such cases have brought about a style trend wherein it is desired to have 60 exposed metallic parts which may be given a highly polished, engraved or other decorative finish, which parts have introduced many difficulties in manufacturing. One of these difficulties is that of forming an inexpensive smoothly finished case wherein the edges of the flexible covering material adjacent the exposed metallic parts of the case will not become loosened or frayed during use. Most cases of this nature, in the past, were formed by securing a separate 65 metallic part to the case after it had been covered in the usual prior art manner. This process was not only very expensive but the metallic parts extended outwardly beyond the surface of the covering material and formed an irregular and 70 undesired finish. It, therefore, is one of the prime objects of this invention to provide a case of the above character wherein the said case will have exposed metal parts blended with the flexible covering material of the case in such a manner 75 that the said material will lie flush with the exposed faces of the metal and be protected along its peripheral edges by said exposed metal parts so that it will not become loosened or frayed during use.

80 Referring more particularly to the drawing wherein like characters of reference designate like parts throughout the several views, the device embodying the invention comprises a main box portion 1 having a cover member 2 hinged 85 thereto throughout its rear edge as shown at 3.

The cover 2 is formed from a sheet of material such as aluminum, steel, silver, gold, or other suitable means, which is blanked to the desired contour shape and is then pressed or otherwise 90 shaped with a central depressed portion 4 having a raised marginal reenforcing edge portion 5 along the front and sides thereof. The central depressed portion 4 extends outwardly to the rear marginal edge of the case and terminates in a 95 portion of the hinge member 3. This forms a shouldered depression 4 in which the flexible covering 6 of the case may be fitted as shown in Fig. II. The cover 2 may if desired, during the forming of the marginal portion 5, be formed with a 100 raised portion 7, as shown in Figures I and II, to provide a surface on which a monogram or other means may be placed.

105 The flexible covering 6 may be formed of genuine leather, imitation leather, fiber, cloth or 110

other suitable material cut or otherwise formed to the desired contour shape and size and is secured throughout the entire outer area of the main box portion 1 by an adhesive or other suitable means in the usual prior art manner. The covering is in secured relation with the case from the edge 8 on the inside of the lip portion 9 to a point 10 outwardly of the case and adjacent the rear edge of the box portion 1. The said flexible covering from the point 10 upwardly of the back of the case is unsecured up to a point 11 wherein it is secured to the cover portion 2 throughout its entire contacting area with said cover portion. The flexible covering 6 throughout its peripheral edges 12 is adapted to abut with the shouldered portions 13 of the cover. If desired the covering 6 may be secured at the said abutting edges by a cement or other suitable adhesive similar to that used in securing the said covering to the surface 4 of the cover. To aid in increasing the adhering action of the cement or adhesive used in securing the covering 6 to the cover portion 2, the said depressed area 4 is roughened as indicated at 14.

25. The sides 15 of the box portion 1 are covered with the flexible material 6 which is brought upwardly of said sides and turned inwardly in a manner similar to that shown at 8 on the lip 9. The covering material 6 is shaped at 16 at each 30. end of the case to underlie the loose portion 17 of said covering at the hinged side of the case.

35. The box portion 1 and cover 2 are provided with a lining member 18 of velvet or other suitable means which is secured internally thereof by a cement or other suitable adhesive in the usual manner.

40. Attention is directed to the fact that in the finished article the flexible covering material covers the entire box portion 1 and extends upwardly into the depression 4 of the cover member 2 through the depressed marginal portion at the hinge side of the case and that the covering material 6 is shaped to fit and lie in the depressed portion within the marginal rim 5. In 45. instances where there is a raised portion 7 provided such as shown in Figures I and II the covering material 6 is cut out to fit snugly about said raised portion.

50. From the foregoing description it will be seen that simple, efficient, and economical means and process have been provided for accomplishing all of the objects and advantages of the invention.

Having described my invention I claim:

55. 1. In a device of the character described, a box member and a cover member hinged to said box member, one of said members having its central portion depressed and having a marginal rim on all sides except the hinge side and a flexible covering on said members, said flexible covering extending from one member into the depression in the other member through the depressed marginal portion on the hinge side thereof and being shaped to fit and lie in the depressed portion within the marginal rim.

60. 2. In a device of the character described, a box member and a cover member hinged to said box member, one of said members having a raised marginal portion on all sides thereof except the hinge side and a flexible covering on said mem-

bers, said flexible covering extending from one member to the other member over the hinged side and being shaped to overlie said last named member with its peripheral edges abutting the edges of the raised marginal portions.

65. 3. In a device of the character described, a box member and a cover member attached at one side to said box member, one of said members having a raised shouldered marginal portion on all sides thereof except the attached side and a flexible covering on said members, said flexible covering extending from one member to the other member over the attached side and being shaped to overlie said last named member with its peripheral edges abutting the shouldered edges of the raised 90 marginal portions.

70. 4. In a device of the character described, a box member and a cover member attached at one side to said box member, one of said members having its central portion depressed and having a marginal rim portion on all sides thereof except the attached side and a covering of sheet material on said members, said sheet material extending from one member into the depression in the other member through the depressed marginal portion on the attached side and being shaped to fit and lie in the depressed portion within the marginal rim.

75. 5. In a device of the character described, a box member having a cover member hinged thereto, said cover member having a central depressed portion extending outwardly to the hinged edge thereof and having raised marginal edges on the sides and edge opposite the hinged edge, and a covering of sheet material secured to the box member and extending from said box member into the depression in the cover member through the depressed edge on the hinge side of said cover member and being secured to said cover member within the raised marginal edges.

80. 6. In a device of the character described, a box member and a cover member hinged to said box member, one of said members having a raised marginal rim portion on all sides but the hinge side adapted to form a depressed area within said rim portions which extends outwardly to the hinged edge of said members, and a covering material on said members, said covering material extending from one member over the hinged side of said members into the depressed area of the other member and being secured in said depressed area with its outer surface substantially flush with the exposed surface of the rim portion.

85. 7. In a device of the character described, a box member having a cover member hinged thereto, one of said members having a raised portion thereon, said raised portion having a surface which lies in a different plane but substantially parallel with the surface of said member, and a covering of sheet material on said members, said covering extending from one member over the hinge side of said members and over the surface of the other member having the raised portion thereon and having an edge portion abutting a side of said raised portion with the exposed surfaces of said raised portion and the covering material lying substantially flush with each other.
